UNITED STATES PATENT OFFICE

ROBERT HILL, OF AYLMER, QUEBEC, CANADA

METHOD AND APPARATUS FOR SORTING AND DISTRIBUTING MAIL AND THE LIKE

Application filed October 21, 1929, Serial No. 401,288, and in Canada September 26, 1929.

This invention relates generally to methods and apparatus for sorting and distributing mail and other matter of various kinds, and more particularly to apparatus for carrying out the method, which is fully described in a separate and co-pending application for patent.

The general object is to provide apparatus of this kind which will function economically and operate automatically while speeding up the primary separation of mail and the like, and more particularly letter mail.

One of the essential objects of the invention is to provide a mechanical distributing member into which letter mail is placed and sorted, and from which it is automatically discharged in sorted condition for distribution for final destination points and to secondary or auxiliary distributing members.

With the foregoing and other objects hereinafter more fully referred to, the novel features of the invention comprise a movably mounted member and a fixedly mounted member including a plurality of spaced partitions suspended at a predetermined angle relative to the movable member, whereby sorting troughs with a common movable base are provided to remove letters and the like and cause same to automatically assume a predetermined position on being placed therein, means integral with the troughs for retaining the letters in such predetermined position in transit and for automatically discharging the letters, sorted.

Referring to the drawings in which like numerals of reference indicate corresponding parts in each figure:

Fig. 1 is a plan view of the distributing member.

Fig. 2 is a side elevation partly in section.

Fig. 3 is a vertical section through center of the distributing member.

Fig. 4 is a sectional elevation showing the connection between the distributing member and the stackers.

Fig. 5 is an enlarged detail of the separators for the stacker belts.

Fig. 6 is an enlarged detail in sectional elevation of the standard and bearing for the distributing member.

Fig. 7 is a plan view of same.

Referring now more particularly to the drawings, in which an example of the apparatus is disclosed, A designates the distributing member as a whole, and B the supporting standard, comprising the hollow standard B adapted to be fixedly mounted in any suitable manner to a floor or the like. On the hollow standard B, is a sleeve or outer hollow member 11 threaded at both ends, as at 12, and adapted to rotate the standard by means of ball bearings 13 and 14. These bearings are held in position by collars 15 and 16 and the rings 17 and 18 spaced therefrom and connected thereto by bolts 19 and 20. The rings and collars are all associated with the member 11, while on the fixed standard B is a collar 21 through which extend adjusting screws 22, adapted to engage with the bearings 14. The collar 16 screw-connected to member 11 is formed with a groove 23 to engage with a bolt or the like for driving the apparatus and hereinafter more fully referred to.

Between the adjustable collars 15 and 16 on the member 11, are designed to fit the nose shaped and squared ends of a plurality of supports 24 of any suitable material, and rigidly held in position by said rings. These supports extend fan like from the member 11 which forms a hub and are of substantially triangular shape to carry a slanting top and to provide in combination therewith, the rotatably mounted truncated cone member 25.

The extreme top or apex of the member 25 is preferably, as here shown, recessed or saucer shaped at 26, while beneath this member, and in spaced relationship thereto, is a supporting table or platform 27 conforming to the contour of the member 25.

Suspended above the member 25 in cantilever fashion and in rotatable relationship thereto, by means of spaced ribs 29, fixedly secured in any well known manner to the table 27, are a plurality or series of spaced partitions 30 suspended circumferentially and, as here shown, almost completely around and above the member 25, providing a gap 31 between the closed ends 32 and the downwardly extending run off opposite ends 33. This gap

31 may, if required, and under certain conditions, be entirely eliminated and the partitions 30 carried continuously around. Furthermore, the partitions may be varied in dimensions and in numbers to suit conditions and the matter or material for sorting and distribution in transit. In the present example of my invention, the gap is used to accommodate an automatic stacker (not shown) whereby the cancelled mail matter is retained in close proximity to the center of the distributing member A. It will be understood, however, that it is also adapted to any other suitable means for retaining matter other than mail, ready for delivery to the distributing member. For example, with modifications as suggested above in the construction of the partitions, the top of the member 25 may be used to accommodate a hopper or the like to which matter or material for sorting would be delivered in any well known manner, and from which it would be taken to the partitions, where it would be automatically sorted and at the same time progressively moved. The automatic stacker forms the subject matter for a separate and co-pending application, it is, therefore, not deemed necessary to enter further into the details of construction in this application.

10 The fixedly suspended partitions 30, forming in combination with the member 25, sorting troughs with a movable common base and the special construction of these partitions, as well as their angle of relationship to the member 25, as hereinafter more fully described, comprise essential and basic features of the improved master distributing member. It may here be mentioned that the ribs 29 are so arranged as to perform a double function, by fixedly suspending the partitions and vertically dividing the top surface thereof into sections opposite to each of which a sorter may be seated for handling the mail.

15 As disclosed in Figs. 1 to 4 inclusive, the partitions 30 are adapted to form with the rotating member 25 the troughs 34, each of which is, as shown, labeled or otherwise marked, as at 35, (see Fig. 2) to indicate a destination point for letters or the like, thereby enabling the sorters to see at once where they are to place the letters.

20 Referring now to the construction of the partitions 30, which with the specially prepared gripping surface of the member 25, and their angle of application thereto, automatically cause letters deposited in the troughs 34, to immediately assume a position on edge, and while moving to automatically retain same in this position until discharged under the influence of the progressive movement through the run offs 33 and by gravity. This is also another basic feature of my invention and is provided for by their angle of application and the twist and curvature of

the troughs, in combination with the downwardly extending run off ends 33.

It will further be noted that while the partitions 30 are at substantially right angles to the surface of the member 25, they are curved or twisted adjacent the downwardly extending run off ends 33, as at 36, whereby on letters travelling therein on edge, as already described, reaching this point and being in touch with one of the side walls of a trough, they will automatically move still on edge to contact with the opposite side wall and thus obviate any tendency to be caught between the rotating surface of the member 25 forming the bottom of the troughs, which is rotatably spaced therefrom, as at 37. From the curvature or twist 36, the troughs are straight with a downward slant to individually engage with a series of automatic stackers 38 (see Fig. 1), provided with star wheels operatively retaining arms and of well known construction. These stackers are driven by a roller 39 which may be provided with discs between each of which of the stacker belts, the roller 39 being provided with a pulley 40 connected by a belt 41 to a prime mover, or the like (not shown). I also provide, as illustrated in Fig. 5, substantially V shaped separators 42 adapted to detachably fit into a retaining member or board 43 and connected together by a rod 44. A series of belts 45, operating between the members 42, carries the mail to the stackers 38.

25 For the top of the fixed standard B, I provide a cap 46 of any suitable construction to which are rigidly anchored supporting braces 47 for the ribs 29.

30 In the present example of the invention, the operation is as follows: A motor or the like (not shown) for driving the member 25, is brought into action to rotate this member at any desired speed through the belt 45 and collar 16. The letters are then taken from a stacker by the sorters sitting around the table 27 and dropped into the different troughs or compartments 34, according to the destinations to which the letters are ultimately delivered. Troughs for letters for final destination points and for further primary separation are being designated accordingly. All are dumped by the sorters into the troughs 34, where they at once assume a position on edge travelling around in the troughs until they reach the twist or curve 36 adjacent to the run offs where the letters automatically and still on edge change from one side of a trough to another, and then shoot out in the downwardly slanted run off portions of the troughs, under the influence of the speed imparted to them while in transit through the troughs, as well as by gravity, where those letters for final destination points drop sorted onto the automatic stackers 38 for removal accordingly, while those letters for further primary separation, are dropped on to com-

5 bined conveyor trough and stacker mechanism, forming the subject matter of a separate co-pending application, in turn communicating with subsidiary or auxiliary distributing members from which they are ultimately discharged and stacked for final destination points. It will be understood that while the device is here shown and described as used for the speeding up of post office operations 10 in the sorting and distribution of letter mail, that it can also, without departing from the spirit or scope of the invention, be applied to the mechanical sorting distribution of other matter and material with equally satisfactory 15 results. For example with slight modifications involving only a reduction in the number of troughs, the sorting and distributing member may be adapted and used as an improved mail facing machine, and as such, 20 will more efficiently perform the functions heretofore carried out by existing devices of this description.

It should also be noted that as the letters are dropped into the sorting troughs they will 25 automatically, due to the angle at which these troughs are fixed relative to the cone-shaped member forming the moving base, assume a position on edge as they circulate around in the trough, while at the same time, the speed 30 at which they travel in the troughs is automatically increased from the moment the letters are thrown in until they are discharged by the whirling movement of the cone-shaped member. In other words, as the letters come 35 in contact with the rotating base of the troughs, they will at the first contact naturally move slower than after being spun around within the trough and the impetus or speed thus given materially assists in the subsequent 40 discharge of the letters to the stackers and conveyors.

As many changes could be made in the above construction and many apparently 45 widely different embodiments of my invention, within the scope of the claims constructed without departing from the spirit or scope thereof, it is intended that all matter contained in the accompanying specification and drawings shall be interpreted as illustrative 50 and not in a limiting sense.

What I claim for my invention is:

1. In a sorting and distributing apparatus for mail, the combination with a substantially cone-shaped rotatable member of a plurality of bottomless troughs of resilient material fixedly mounted in co-operative relationship with the rotating member and controlled means for operating the rotating member.
2. A master sorting and distributing apparatus for mail comprising a plurality of fixedly mounted resilient troughs and a rotatably mounted cone-shaped member beneath said troughs forming a common base for the troughs.

3. A sorting and distributing apparatus comprising a rotatable cone shaped member and a fixedly mounted sorting member co-operating with the rotating member and comprising a plurality of substantially circularly spaced guideways in operative relation with and at a predetermined angle to the rotatable member. 70

4. A combined sorting and distributing member comprising a plurality of fixedly mounted suitably curved partitions, a rotatably mounted substantially cone shaped member co-operating with said partitions to form troughs with a movable common base and controlled means for moving the base. 80

5. The invention according to claim 4 in which the fixed partitions are at right angles relative to the surface of the rotating member.

6. The invention according to claim 4 in 85 which the partitions are open at one end and downwardly extended to form run offs.

7. The invention according to claim 4 in which the partitions are suitably curved or twisted adjacent one end to further automatically retain selected material in transit 90 therein in a predetermined position.

8. In a combined sorting and distributing device the combination with a series of fixedly mounted substantially circular guideways 95 of a rotatable suitably surfaced cone-shaped member beneath said guideways to form a common movable base therefor, said guideways being at substantially right angles to said rotatable member. 100

9. The invention according to claim 4 in which the troughs are individually marked to indicate different destination points for letters and other matter deposited therein.

10. A combined sorting and distributing 105 apparatus comprising a rotatable cone-shaped member, a plurality of fixed partitions adapted to form with said member, troughs, controlled driving mechanism for moving said member, whereby on mail matter and the like being deposited in said troughs, a predetermined accelerated movement is automatically imparted thereto. 110

11. A combined sorting and distributing member comprising a rotatable truncated 115 cone, a plurality of fixed suitably formed partitions with indicia thereon adapted to form with said member, sorting troughs, said troughs having open run off ends, means for operating said cone, whereby on mail 120 matter and the like being deposited in the troughs, an accelerated movement is automatically imparted to such mail, and means for automatically discharging the matter from the troughs under the influence of the 125 speed imparted thereto.

12. In a master sorting and distributing member for letter mail, a rotatably mounted cone-shaped member with a suitable surface, intermediately bent and suitably curved par- 130

- titions fixedly suspended in proximity to said member and at a predetermined angle thereto to form a series of troughs with said member, whereby on said member being rotated an accelerated movement is automatically imparted to matter deposited in the troughs, and whereby such matter so deposited automatically assumes a predetermined position and is automatically returned in such position while in transit therethrough.
13. In a master sorting and distributing member, the combination with a rotatable cone member provided with a gripping surface, of a plurality of spaced partitions fixedly suspended at a predetermined angle relative to the said member to provide sorting troughs of suitable dimensions with a common movable base and controlled prime-mover means for operating the movable member.
14. In master distributing apparatus for mail matter and the like, the combination with a suitably formed table, of a rotatable truncated cone member in spaced suspended relationship to said table and a plurality of concentrically arranged partitions fixedly suspended in operative relationship to said member.
15. In master distributing apparatus for mail matter and the like, the combination with a rotatable truncated cone member, of a plurality of concentrically arranged partitions fixedly suspended in operative relationship relative to said member, means formed in the cone for receiving and holding mail matter prior to being sorted into the partitions, and means integral with the partitions for automatically retaining mail matter sorted thereinto, on edge and for automatically discharging such mail matter at substantially right angles to the direction of travel of the cone member.
16. A master distributor and momentum generator for mail matter and material comprising a rotatable truncated cone with a recessed apex, a plurality of fixedly suspended troughs concentrically arranged in operative relationship to the cone, said troughs being intermediately bent and formed with discharge chute portions at one end.
50. In witness whereof I have hereunto set my hand.

ROBERT HILL.
